UNITED STATES PATENT OFFICE.

JOHN THOMSON, OF NEW YORK, N. Y.

ELECTRIC ZINC-FURNACE WITH INTEGRAL CONDENSER.

1,080,865.

Specification of Letters Patent.

Patented Dec. 9, 1913.

Application filed January 2, 1913. Serial No. 739,794.

To all whom it may concern:

Be it known that I, JOHN THOMSON, a citizen of the United States, and a resident of the borough of Manhattan of the city of New York, in the county and State of New York, have invented certain new and useful Improvements in Electric Zinc-Furnaces with Integral Condensers, of which the following is a specification, reference being made to the accompanying drawings, forming a part hereof.

This invention relates to the metallurgy of zinc, having for its object the production of zinc fume which is subsequently condensed to liquid metal.

A description of the particular means for attaining the desired results and such an elucidation of the general principles applicable thereto as will provide a complete disclosure of the invention will be concurrently pointed out in connection with the description of the accompanying drawings, which represent a preferred embodiment of the invention.

25 Figure 1 is a transverse center section of the furnace, as A or A¹ of Fig. 2; Fig. 2 is a longitudinal center section, as B or B¹ of Fig. 1, and Fig. 3 is a detached plan view of a terminal.

30 This furnace is particularly intended for the reduction of oxid of zinc combined with carbon as the reagent whereby when adequately heated substantially the following representative reaction ensues, namely:

If pure ZnO and C are used in precisely correct relative proportions then the answer of the above formula is an exact expression of the result in that all of the charged material would be volatilized as zinc fume and monoxid of carbon, in which case there would be no residue. Such conditions, however, do not obtain in commercial practice as more or less inert residual matter will remain, depending upon the purity of the materials employed, and hence the formula becomes as above stated simply representative. The presence of this residual matter is a cause of difficulty in realizing a successful result.

The heat necessary for decomposing the charge is preferably derived by direct conduction of heat from a "resistor" H formed by a bed of broken carbon interpolated between terminals suitably connected to a

power circuit. The charge material P is fed to the upper surface of the resistor through transverse slots or galleries 5 formed by tiles or slabs 6. It will be observed that the lower edges 7 of the slabs do not quite reach to the surface of the resistor and that they are wide enough so that when the galleries are filled with charge material transverse spaces 8 will be provided into which the volatilized products of the reaction are free to flow. According to the foregoing system the resistor is virtually divided into alternating cross sectional zones, one for the down-flow therethrough of the fume and gas, and the other for inert residual matter, and so on throughout the length of the bed.

The condenser is chiefly comprised in a condensing "resistor" or a filter bed I, as the case may be, supported by spaced grate bars 9 resting upon ledges 10 and which may also have a central support, as by means of plates 12, perforated as at 13, to permit a free interchange of fume and gas from one side to the other. Upon the upper surface of the resistor filter bed one or more series of spaced cross stacked bars or rods are placed, as a transverse series 14 and a longitudinal series 15 which serve in turn to support the reaction resistor H. Thus the reaction system and the condensing system are both contained in a single chamber, in other words the filter bed lies directly beneath and serves to sustain, through the intermediary grill of rods, the reaction resistor.

In the bottom of the condensing chamber is a bath of molten zinc 16 with a free chamber as e between the bath and the grate bars, whose spaces as 17 are in communication with the said chamber.

Beneath the bottom of the condensing chamber is a sub-divided flue T, T¹ in which fuel heat or cold air may be circulated, as through the tubes 18, 18¹ for the purpose of controlling the temperature of the bath.

Extending along each side of the furnace to the full extent of the height and length of the chamber in which the reaction resistor and the filter bed is contained, are chambers or galleries C, C¹, the bottoms of which are connected by a series of right and left hand ports, as 19, 20, to the space e, and from the tops of which are tubes as 21, 22, leading to atmosphere. These galleries are entirely

unobstructed except with such necessary thrust pieces 23 as may be required for obtaining stability of the walls.

The operation is as follows: When the reaction is under way, all of the products thereof must pass down through the bed of carbon resistor, the volatilized products through the several zones provided therefor and the same as to the inert residue. In this wise, if any pernicious oxidizing medium such as CO_2 is produced at and escapes from the seat or seats of the reaction, a secondary or "cleansing" reaction will take place in passing through the incandescent carbon bed, and if the evolution is more rapid at one "seat" than the other the fume and gas will expand and equalize when the spaces between the rods are reached, as 24, 25. The upper surface of the filter bed will have a temperature, by radiation and conduction, approximating that of the lower surface of the reaction resistor, but from thence down to the grate bars the temperature progressively decreases by conduction of heat to and through the bath to a point somewhat above that at which the liquid metal is maintained. Consequently the so-called filter bed plays the additional role of presenting a large diffusing surface and also a considerable mass of material possessing a high capacity for the absorption of and the downward conduction of the heat contained in the fume and gas. After having reached the grate bar spaces the condensed zinc and volatile matter impinges upon the bath and any residual gas or fume passes from the space e through the ports 19, 20, into the galleries C, C¹, and thence to atmosphere by the tubes 21, 22. The flow through the galleries will be relatively quite slow, hence if any fume has been entrained by the CO it will again have opportunity to precipitate into the troughs s either as fluid or "blue powder" or both. As these galleries quite "blanket" the sides of the resistor and the filter their heat will be largely conserved for useful effect. The monoxid of carbon in the side galleries also serves to prevent any infiltration of air through the outer furnace walls.

The obstruction to the flow of the fume and gas produced by the friction of the interstitial spaces in the resistor and the filter, may be partially or wholly nullified by means of natural or artificial draft applied to the tubes which may also be provided with dampers or valves, as 26, for the purpose of regulation, also to exclude a back flow of air, as when repairing or suspending the operation of the furnace and to force a flow of CO to the small test pipe 27.

When a good quality of igneous oxid and reaction coke is employed the inert residual matter will be of relatively small volume and usually in the form of a fine ash or granu-

lated sinter. This material finds its way down through the voids in the resistor and thence down through the filter. A certain amount thereof may lodge in portions of the spaces between the crossed rods.

The material of which the crossed rods are formed is preferably of re-crystallized carborundum (SiC) which serves the additional function of somewhat electrically insulating the resistor from the filter. Consequently, it becomes feasible to provide the "filter" with terminals, as 28, whereby it may be separately utilized as a "resistor". Several advantages of controlling importance are derived from this. Thus in starting up a furnace the filter bed may be pre-heated to a proper temperature before the reaction takes place. Again, if the rate of evolution of fume and gas is such that the temperature of the filter might fall to the "freezing" point of zinc, sufficient energy may be sent therethrough to avoid this. Finally, if an excessive accumulation of inert residue takes place either on top of or in the filter, a high input of current may be temporarily injected sufficient to disintegrate any agglomerated sinter, or by the addition of a suitable flux, to fuse it.

As doubtless will have been perceived, the inert residue may pass down to and floats upon the zinc bath which is preferably maintained at about a constant level, and this can be readily accomplished as by means of a siphon 29 or by intermittent tapping as denoted by the tap hole 30. At longer intervals when there is a considerable accumulation of residue the blocks 31, 32, may be removed and the residual matter may be scraped out through the large openings 33, 34.

The reaction resistor and the filter bed may be electrified by separate circuits or they may be in parallel or in series in the same circuit or the filter bed may be otherwise incited as from a shunt circuit.

In the present case a preferred mode of forming the contact ends of the terminals 8 or 28 is shown in Fig. 3 and consisting in providing crosswise of their faces the V notches r . In this way an enlarged surface area is provided and the carbon may settle downwardly without sensibly affecting the integrity or efficiency of the contacts.

Various modifications may be made in the details without departing from the essential principles herein shown and described; thus for example, instead of causing the filter bed to directly support the reaction resistor the latter may rest upon a distinct grating mounted upon ledges, as in the instance of the grate bars 9, and an expanding chamber 9 may be thus readily provided between the upper and lower surfaces of the two carbon beds; or, again, the rod grill may be substituted by pieces of broken carborundum.

What I claim is:

1. In an electric zinc furnace, a bed of carbon reaction resistor supported on a filter bed.
- 5 2. In an electric zinc furnace, a bed of carbon reaction resistor, a carbon filter bed and an interposed spaced grill formed of rods.
- 10 3. In an electric zinc furnace, a bed of carbon reaction resistor and an underlying carbon filter bed supporting the resistor, said bed resting upon a grate.
- 15 4. In an electric zinc furnace a zinc receptacle, a spaced grating above said receptacle, a filter bed resting upon said grating, and a carbon resistor supported on said filter bed.
- 20 5. In an electric zinc furnace, a bed of carbon reaction resistor, a carbon filter bed and an interposed spaced grill or grating of lesser electrical conductivity than the overlying and underlying carbon.
- 25 6. In an apparatus comprising an electric zinc furnace and condenser, a system of spaced grate bars, beneath which is a bath of molten metal and a free chamber, an overlying carbon filter bed, a separating grill or grating, and a bed of carbon reaction resistor for receiving thereupon a charge of oxid of zinc and carbon, said apparatus being constructed so that all of the products of the reaction passing downwardly toward and finally impinging upon the said molten bath.
- 30 35 7. In an electric zinc furnace, a bed of carbon reaction resistor, a carbon filter bed and a bath of molten metal, all contained in a common chamber.
- 35 8. In an electric zinc furnace, a bed of carbon reaction resistor, a carbon filter bed, a bath of molten metal, all contained in a common chamber, and blanketing side galleries into and through which the residual volatilized products of the reaction are caused to flow.
- 40 45 9. In an electric zinc furnace, a chamber containing means for producing the reaction, means for effecting condensation of fume, galleries on opposite sides of the reaction chamber, a port or ports for connecting the chamber to the galleries, and openings for conducting the residual volatile product or products to atmosphere.
- 50 10. In an electric zinc furnace, a bed of carbon reaction resistor electrically separated from an underlying carbon filter bed which may be electrified.
- 55 11. In an electric zinc furnace having a system of spaced grate bars, a carbon filter bed, a superimposed bed of carbon reaction
- resistor and a system for supplying the charge in distinct layers, whereby the said resistor and filter are separated into alternating transverse zones through which the volatile and the inert products of the reaction are caused to pass in a downward direction side by side. 65
12. In the metallurgy of zinc an electric furnace having in one chamber an electric resistor which is utilized to create heat for the purpose of causing reaction in the charge, thus producing zinc fumes, and under the resistor a carbon filter through which the zinc fumes pass downwardly to the underlying zinc bath. 75
13. In the metallurgy of zinc a furnace having in the reaction chamber thereof a bed of carbon resistor below which is located a carbon filter over a metal bath, the filter and the bath being located in the same chamber as the resistor. 80
14. The combination in an apparatus of the class described, a reaction chamber provided with a resistor for producing zinc fumes when sufficient electric current flows through the resistor and beneath the resistor a fume condensing means comprising broken carbon supported on a grate located over a liquid zinc bath. 85
15. In an electric zinc furnace a charge of reaction material, a primary reaction resistor and a secondary resistor, the primary resistor being sustained by the secondary resistor and the zinc fumes passing downwardly from the zone of the reaction through both of said resistors during the process of condensation. 90
16. In an electric zinc furnace a charge of reacting materials, a primary reaction resistor and a secondary resistor, the primary resistor being sustained on the secondary resistor and the volatilized and residual products of the reaction passing downwardly through the zone of the reaction through both the said resistors during the process of condensing the zinc fumes to liquid metal, the furnace also being provided with a bath of liquid zinc over which the fumes must pass before the residual fumes leave the condenser. 100
17. In an apparatus of the class described, a bed resistor located over a second resistor of broken carbon, said resistors being separated by a grill of cross members. 110
